FRANCIS A. JIMERSON, OF ATHENS, PENNSYLVANIA, ASSIGNOR TO INGERSOLL-RAND COMPANY, OF JERSEY CITY, NEW JERSEY, A CORPORATION OF NEW JERSEY.

RATCHET OPERATING MECHANISM FOR DRILLS.

1,255,315.

Specification of Letters Patent.

Patented Feb. 5, 1918.

Application filed June 19, 1915. Serial No. 35,109.

To all whom it may concern:

Be it known that I, FRANCIS A. JIMERSON, a citizen of the United States, residing at Athens, in the county of Bradford and State 5 of Pennsylvania, have invented a certain new and useful Improvement in Ratchet Operating Mechanism for Drills, of which the following is a specification.

This invention relates to fluid operated 10 rotary drills, and more particularly to drills of this type known as "close corner drills," which are designed to operate in restricted spaces, and particularly relates to improvements in the type of drill shown in the 15 patent of Caid H. Peck, No. 1,172,901 granted February 22d, 1916.

These drills, as usually constructed, consist of an elongated casing in the extremity 20 of one end of which is located a rotary spindle which is generally operated by a series of ratchet levers driven through the medium of small reciprocating motor elements set in the other end of the casing.

One object of the present invention is to 25 provide a ratchet mechanism which will allow the ratchet teeth on the spindle to be of considerable size, and consequent strength, and yet, at the same time, permit a rapid movement of the motor pistons in 30 comparison to the movement of the spindle, thus enabling the motor elements to be of small size and yet produce a powerful and continuous torque on the spindle. This result is accomplished by having the pawl of 35 each ratchet lever of the series successively engage the same tooth of the spindle, in contradistinction to the usual construction in which the pawl of each ratchet lever engages a new tooth of the spindle.

40 A further object of the invention is to provide a construction having the motor pistons engaging and actuating the ratchet levers without the interposition of intermediate elements in which means are provided to definitely control the respective 45 positions of the ratchet levers with regard to each other and, at the same time, limit and control their angular movement with respect to the drill spindle.

50 A still further object is to provide an arrangement for the ratchet levers and their

driving motors whereby a plurality of motors and ratchet levers having equal power can be arranged in a restricted space.

With these, and other objects which will 55 further appear, in view, a drill has been devised, a practical embodiment of which is shown in the accompanying drawings, in which,

Figure 1 is a side view, partly in section, 60 on the line 1—1 of Fig. 2, and partly broken away to show the ratchet levers and motor mechanism in side elevation.

Fig. 2 is a longitudinal horizontal section on the line 2—2 of Fig. 1, and 65

Fig. 3 is a diagrammatic view showing the ratchet mechanism and the positions of the pawls in the various ratchet levers.

The drill, as shown, comprises an elongated casing 1, at one extremity of which 70 is a cylindrical spindle sleeve 2, the ends of which project above and below the casing 1. In this spindle sleeve 2 is rotatably supported the spindle 3, this spindle having an upper bearing portion 4, a central toothed 75 portion 5 and a lower bearing portion 6, these being all of the same outer diameter. The bearing portion 6 is journaled in a bushing in the lower part of the sleeve 2, while the bearing portion 4 is journaled in 80 a bushing 7 which has an upper flange 8 resting on a shoulder in the sleeve 2. The spindle 3 is provided at its upper end with a flange 9 which rests on the upper face of the bushing 8, thus preventing movement of 85 the spindle in a downward direction, while movement of the spindle in an upward direction is prevented by a cap 10 threaded into the upper end of the sleeve 2, a ball set 11 being inserted between the flange 9 90 and the cap 10. In the cap 10 is secured a telescopic feed screw mechanism 12, the details of which form no part of the present invention. Extending longitudinally of the casing are three ratchet levers 13, 14, and 15. 95 The spindle ends 16, 17 and 18 of these levers form circular sleeves or straps which surround the toothed portion 5 of the spindle, the spindle forming a bearing or fulcrum for the oscillation of the levers. At 100 the other end of the casing are three cylinders 19, 20 and 21 whose axes are set at

right angles to the length of the casing and at right angles to the longitudinal axis of the spindle. Reciprocating in the cylinders are pistons 22, 23 and 24, each of which consists of a piston element 25 and a connecting rod element 26 which is in the form of a pin rigidly secured in the inner side of the piston element and having a longitudinal slot 27 in its outer end into which projects a knob 28 on the end of the lever which is actuated by this particular piston, this knob being free to slide in the slot 27 to allow for the longitudinal movement due to the oscillation of the levers. The three cylinders 19, 20 and 21 are not set on the same line with respect to the spindle but the inner cylinder 20 is set nearer the spindle and somewhat between the other two, so that the cylinders overlap to a certain extent on the line of the spindle axis, enabling the end of the casing to be of considerably less height than if the cylinders were all on the same line. This arrangement of the cylinders also has the advantage that the spindle ends of the levers can be close together and yet the cylinder ends of the upper and lower levers need not be at any considerable angle from the spindle axis. Since by this arrangement of the cylinders the central lever 14 must be of less length than the upper and lower levers 13 and 15, and consequently the piston 23 must have a shorter reciprocation in order to oscillate the lever 14 through the same angular distance as the levers 13 and 15, the cylinder 20 and the piston 23 are of larger area than the cylinders 19 and 21 and pistons 22 and 24, so that the piston 23 shall exert the same force on the lever 14 as the pistons 22 and 24. To limit and equalize the angular movement of the levers 13, 14 and 15 a crank 29 is provided between the cylinders and the spindle. The casing 1 is split diagonally on the axis of this crank 29, semi-cylindrical bearing seats 30 being thus provided in each section of the casing for the ends of the crank 29 in which are placed ball bearing sets 31 surrounding the ends of the crank. The crank 29 has three offset portions 32, 33 and 34, one for each ratchet lever, set at angles of 120° from each other, these offset portions journaling in split bearing boxes 35 sliding longitudinally in slots 36 in the ratchet levers. This crank mechanism controls and equalizes the amount of angular movement of the levers causing each one to oscillate successively through the same angle of rotation with respect to the spindle. In the levers 13, 14 and 15 contiguous to the spindle 3 are set respectively pawls 37, 38 and 39. These pawls 37, 38 and 39 are not set in their respective levers in the same position with respect to the longitudinal axes of their levers but are so set that each one of the series from top

to bottom will successively engage the same tooth of the spindle. This is accomplished by having the pawl in each lever from the top to the bottom successively advanced over the preceding pawl with respect to the longitudinal axes of the levers an angular amount equal to the angular space occupied by one spindle tooth divided by the number of levers. Taking the specific drill here illustrated as an example and referring to Fig. 3 it will be seen that the spindle is provided with fifteen teeth, each one, therefore, occupying an angular space of 24°. The pawl in the center lever must, therefore, be placed one-third of 24°, or 8°, in advance of the pawl in the upper lever, with respect to the longitudinal axis of the lever, while the pawl in the lower lever must be advanced 8° over the pawl in the center lever with respect to the longitudinal axis of its lever. As shown, the pawl in the upper lever is set 8° rearwardly from the longitudinal axis of its lever, the pawl in the center lever exactly on the longitudinal axis of its lever, while the pawl in the lower is set 8° in advance of the longitudinal axis of its lever, although, of course, the absolute positions of these pawls in their levers is immaterial, their relative positions being the determining feature. It will be evident, therefore, from the above description that as the crank shaft moves in the direction indicated in Fig. 3 the top pawl will engage a tooth of the spindle, move it through a slight angular distance, the pawl in the second lever will then engage the same tooth and move it through the same distance, and the third pawl will complete the cycle, moving the spindle far enough so that the first pawl can engage a new tooth. Theoretically speaking, to produce this cycle each pawl should engage its tooth at a point P which is determined by the number of levers, this point being a number of degrees past the upper limit of the crank's movement equal to 90° minus half of the angular space between the cranks, this distance in the present case amounting to 90° minus 60°, or 30°, and the amount of angular movement of this lever around its fulcrum from the point P to the point P¹, where the next lever comes into operation, should be theoretically equal to the angle through which the lever and its pawl must move the spindle, that is, the angular space occupied by a single spindle tooth divided by the number of levers or in this particular instance 8°, the same angular amount as the pawls are successively advanced with respect to the longitudinal axes of their levers. In practice, however, in order that the first pawl may surely engage a new tooth the throw of the crank 29 must be so calculated with respect to the distances of the pawl and the

crank center from the fulcrum point that the angular distance passed through by the lever in moving from P to P' is slightly greater than the theoretical amount, in the particular example here given being about 9° . This slight amount of clearance is necessary at all loads and particularly so when the drill is under heavy loads at which times the cylinder ends of the levers are slightly bent or flexed forwardly due to the stress. The reciprocation of the pistons is accomplished by air admitted through an inlet passage 40 and controlled by a rotary valve 41 which is operated through a pinion 42 on the upper end of the crank 29.

The operation of the drill will be evident from the above description. The cylinders 19 and 20 and 21 are successively supplied with air and exhausted by the valve 41. When the lever 13 reaches the point P in Fig. 3, or slightly thereafter, the pawl 37 will engage a tooth of the ratchet and exert a continuous turning movement on the spindle until the lever reaches the point P' . During this movement the spindle will have been moved through slightly more than 8° . When lever 13 has reached the point P' , lever 14 will have moved around to the point P , and by reason of the advance of the pawl 38 in this lever over pawl 37 in lever 13, pawl 38 will engage the same tooth theoretically at the point P , but practically slightly later, on account of the slightly more than 8° movement of the lever 13. Similarly, when the lever 14 reaches the point P' , lever 15 will have reached the point P and the pawl 39 will engage the same tooth as the pawls in the first two levers, also slightly after the lever has passed the point P . When the lever 15 has moved around to the point P' the lever 13 will have again moved around to P and its pawl will be in a position to engage the next tooth of the spindle. It will be seen, therefore, that there is a practically constant torque on the spindle which results in a very powerful movement of the spindle which is comparatively slow with respect to the movement of the pistons. It will be evident that if the three pawls did not engage the same tooth successively, there would have to be three times as many teeth to get the same slow speed and high power, and the teeth would be consequently so small that they would be unable to properly transmit the amount of power necessary without prohibitive wear and breakage. The provision of the crank connecting the various levers allows the regulation and control of the respective positions of the levers and limits and equalizes their angular movement, as well as furnishing positive mechanical control of the valve 41.

It is to be understood that while the present showing and description disclose only

one specified modification of this present invention, other forms and modifications are included within the spirit and scope thereof, as expressed in the appended claims.

What I claim is:

1. In a close corner drill, a ratchet mechanism comprising a spindle having teeth thereon, a series of pawl carrying levers, directly connected means to oscillate said levers around said spindle successively through the same angle of rotation and pawls set in said levers engaging said teeth, the pawl in each successive lever of the series being advanced with respect to the longitudinal axis of its lever an angular amount in the direction of the spindle rotation equal to the angular space occupied by a single spindle tooth divided by the number of levers.

2. In a close corner drill, a ratchet mechanism comprising a spindle having teeth thereon, a series of pawl carrying levers, means to oscillate said levers around said spindle successively through the same angle of rotation and pawls set in said levers engaging said teeth, the pawl in each successive lever of the series being advanced with respect to the longitudinal axis of its lever an angular amount in the direction of the spindle rotation equal to the angular space occupied by a single spindle tooth divided by the number of levers, said means for oscillating the levers through the same angle comprising a crank regulating the respective positions of said levers.

3. In a close corner drill, a ratchet mechanism comprising a spindle having teeth thereon, a series of three pawl carrying levers for driving said spindle, said levers arranged to oscillate around said spindle successively through the same angle, and pawls set in said levers engaging said teeth, the pawl in each successive lever of the series being advanced with respect to the longitudinal axis of its lever in the direction of the spindle rotation an angular amount equal to one-third of the angular space occupied by a single spindle tooth.

4. In a close corner drill, a ratchet mechanism comprising a spindle having teeth thereon, a series of three pawl carrying levers for driving said spindle, said levers arranged to oscillate around said spindle successively through the same angle, pawls set in said levers engaging said teeth, the pawl in each successive lever of the series being advanced with respect to the longitudinal axis of its lever in the direction of the spindle rotation an angular amount equal to one-third of the angular space occupied by a single spindle tooth, and means for oscillating the levers through equal angles of rotation comprising a crank mechanism regulating the respective positions of said levers and limiting their angular movement to an

amount slightly greater than one-third the angular space occupied by a single tooth of said spindle.

5. In a close corner drill, a ratchet mechanism comprising a spindle having teeth thereon, a series of pawl carrying levers directly connected thereto, means to oscillate said levers around said spindle successively through the same angle of rotation and

pawls set in said levers engaging said teeth 10 the pawl in each successive lever of the series being advanced with respect to the longitudinal axis of its lever whereby each pawl successively engages the same tooth on the spindle.

15

In testimony whereof, I have hereunto set my hand.

FRANCIS A. JIMERSON.
